Primary Examiner — T Chase Nelson*(74) Attorney, Agent, or Firm* — Cozen O'Connor(57) **CLAIM**

We claim the ornamental design for a shoe sole, substantially as shown and described.

DESCRIPTION

FIG. 1 is a plan view of a shoe sole embodying the design of the present invention shown in an unclaimed shoe; FIG. 2 is a top perspective view of an individual lug taken from the labeled area 2 of FIG. 1, thereof; FIG. 3 is a top perspective view thereof; FIG. 4 is a rear elevation view thereof; FIG. 5 is a front perspective view thereof; FIG. 6 is a side elevation view thereof; and, FIG. 7 is a bottom plan view of thereof, without the detail circle of FIG. 1.

The right foot of an unclaimed shoe environment comprising the shoe sole design is depicted herein. A left foot is a mirror image of the right foot and is not shown.

The broken lines shown in the figures are for purposes of illustrating unclaimed portions of the shoe sole as well as unclaimed environmental structure in the form of a shoe. The broken lines surrounding an individual lug in the FIGS. 1 and 2 indicate the location and boundaries of the enlarged lug shown in FIG. 2. The broken lines form no part of the claimed design.
